UNITED STATES PATENT OFFICE

CLIFFORD C. BUNKER, OF TALLMADGE, OHIO, ASSIGNOR TO THE AKRON STANDARD MOLD COMPANY, OF AKRON, OHIO, A CORPORATION OF OHIO

EXTRUSION APPARATUS

Application filed June 23, 1938. Serial No. 287,711.

This invention relates to machines for extruding heavy plastics such as rubber.

One purpose of the invention is to provide an improved apparatus of this type in which the screw is more effectively mounted to withstand the heavy loads thereon and the bearings and driving instrumentalities are more effectively lubricated.

Other purposes are to provide means for facilitating withdrawal of the stock from the feeding hopper by the screw and improved means for controlling the plasticity of the stock.

The foregoing and other purposes are attained by the apparatus illustrated in the accompanying drawings and described below. It is to be understood that the invention is not limited to the specific form thereof shown and described.

20 Of the accompanying drawings,

Figure 1 is a longitudinal section through a rubber strainer embodying the invention;

Figure 2 is a section on line 2-2 of Figure 1;

25 Figure 3 is a section on line 3-3 of Figure 1;

Figure 4 is a detail elevation, partly broken away to show interior construction of the lubricant pump;

30 Figure 5 is a detail section showing in side elevation the separator for preventing seeping of the lubricant from the bearings;

Figure 6 is a detail section showing the separator in end elevation;

35 Figure 7 is a top plan of the chest for supplying the fluid mediums used for controlling the plasticity of the stock; and

Figure 8 is a bottom plan of the exhaust chest therefor.

40 Referring to the drawings, the numeral 10 designates a suitable supporting structure or base on which is mounted a jacket 11 for an expressing tube 12 in which is operable an expressing screw 13. Jacket 11 is formed with a hopper 14 for delivering the rubber to the expressing tube and a strainer 15 is secured to said jacket through which the rubber is expressed for said tube.

45 Jacket 11 is provided with chambers 16 and 17 extending about the same and adapted to

receive fluid mediums such as steam or water for controlling the plasticity of the stock. To control supply of steam or water to each of chambers 16 and 17, a supply chest 18 is mounted on the upper side of jacket 11. 55 Steam and water pipes are connected thereto respectively at 19 and 20 delivering the steam and water respectively to longitudinal passages 21 and 22 at each side of the chest. Passages 21 and 22 are adapted to deliver either 60 steam or water to either of chambers 16 and 17 by valves 23 and 24 controlling passage of these mediums to a chamber 25 in the chest which is connected by a duct 26 to chamber 16, and by valves 27 and 28 controlling passage 65 of these mediums to a chamber 29 in the chest which is connected to chamber 17 by a duct 30. A further control upon the plasticity of the stock may be had by chambering the strainer 15 at 15^a and 15^b to which 70 piping is connected as shown, whereby cooling or heating mediums may be supplied to the chambers.

An exhaust chest 31 is provided on the under side of jacket 11 having a chamber 32 75 for receiving the fluid medium from chamber 16 through a duct 33 and having a chamber 34 for receiving the fluid mediums from chamber 17 through a duct 35. Valves 36 and 37 respectively are arranged to control 80 flow of the mediums from chambers 32 and 34 to a drain 38.

To effectuate feeding of the material from the hopper 14 by the screw 13, the inner wall of the tube 12 at, and adjacent to, the hopper is formed with grooves 12^a inclined toward the direction of extrusion to resist any tendency for the material to ride around on the screw, and cooperating with the screw to feed the stock forwardly.

The driving of screw 13 is accomplished by the use of worm gear 40 arranged to be driven by a worm 41 both contained in a housing 42 and the gears meshing in a lubricant 95 43 contained in said housing. Worm 41 is journaled in the housing and driven in any suitable way as by motor 44. A cooling coil 45 is arranged in the housing to cool the oil therein.

Gear 40 is journaled upon a central sleeve 100

46 fixed in the housing and is secured to a flange ring 47 keyed upon a quill 48 journaled in said sleeve 46 on end bearings 49 and 50, a thrust bearing 51 being arranged between a shoulder 46^a on sleeve 46 and a shoulder 48^a on quill 48. The screw 13 is keyed directly to quill 48 so that the latter, in effect, is one member of the screw construction, the fit of screw 13 in the key, however, is made 5 lose to permit slight relative rocking of the screw out of exact longitudinal alignment whereby considerable strain is relieved from the bearings and assumed by the wall of the 10 extending passage.

15 Lubrication of bearings 49, 50 and 51 is arranged for by the provision of a pump 52 driven by worm 41, pump 52 being arranged to force oil from the bottom of housing 42 through a connection 53 into a conduit 54 connected to a duct 55 formed in sleeve 46, duct 55 having branches 55^a and 55^b leading to bearings 49 and 51 and a branch 55^c supplying lubricant to bearing 50.

The lubricant is prevented from seeping out of bearing 49 by means of a separate ring 56, the inner periphery of which is wedge-shaped and extends close to the periphery of the quill. Ring 56 carries a separator 57 comprising a block riding on the quill and urged 25 yieldingly against the quill by a spring 58. The end of the separator toward which the quill rotates (Figure 5) is of wedge-shape as indicated at 57*. This construction functions 30 to keep the oil within the ring 56 and to keep 35 dust and dirt of the stock from working into the bearings. A conduit 59 is arranged to deliver oil flowing out through bearing 49 back into the bottom of casing 42. A duct 59* is arranged to deliver dust by gravity 40 from the outside of separator ring 56 through the jacket member 11.

Supply of a heating medium to screw 13 which is hollow is provided for by arranging a central supply pipe 60 through the quill, thus providing a passage 61 about the pipe from which the heating medium may be drained.

Modifications of the invention may be resorted to without departing from the spirit thereof and the scope of the appended claims.

What is claimed is:—

What is claimed is:—

1. In an extruding machine, a screw, a driven quill holder keyed loosely thereto, a sleeve member in which the screw and the quill are journaled, said member supporting therein bearings for the quill at each end thereof and also an intermediate thrust bearing between shoulders on the sleeve and quill, a worm gear journaled about said member and connected to the quill at the end thereof, a driving worm meshed with the worm gear at the bottom thereof, a casing about the gearing defining a reservoir for lubricant about the gears and worms where they are meshed, a pump driven

by the worm, connection to the pump for supplying lubricant from the reservoir to said bearings, a separator acting on the screw beyond the inner end bearing to keep the lubricant in the casing and to keep dirt out of the casing, and a connection between the separator and the inner bearing for returning lubricant to the reservoir.

2. In an extruding machine, the combination with a screw, of a jacketed sleeve member in which the screw is journaled, means for passing fluid through the jackets of said sleeve members, said sleeve member supporting therein bearings for the screw at each end thereof and also an intermediate thrust

end thereof and also an intermediate thrust bearing between shoulders on the sleeve and screw, a gear journaled about said member and connected to the screw at the end thereof, a driving gear meshed with the gear at the bottom thereof, a casing about the gearing defining a reservoir for lubricant about the

gears where they are meshed, a pump driven by the driving gear, connection to the pump for supplying lubricant from the reservoir to said bearings, a separator acting on the screw beyond the inner end bearing to keep the lubricant in the casing and to keep dirt out of the casing, a connection between the

out of the casing, a connection between the separator and the inner bearing for returning lubricant to the reservoir, and a passage on the opposite side of the separator ring from said connection to allow dirt or the like to escape from the machine.

3. In an extruding machine, the combination with a screw, of a sleeve member in which the screw is journaled, said member supporting therein bearings for the screw at each end thereof and also an intermediate thrust bearing between shoulders on the sleeve and screw, a worm gear journaled

sleeve and screw, a worm gear journaled about said member and connected to the screw at the end thereof, a driving worm meshed with the worm gear at the bottom thereof a casing about the gearing defining a reservoir for lubricant about the gears and worm where they are meshed, a pump driven by the worm, and connections to the pump for

the worm, and connections to the pump for supplying lubricant from the reservoir to said bearings.

bearing between shoulders on the sleeve and screw, a gear journaled about said member and connected to the screw at the end thereof a driving gear meshed with the gear at the bottom thereof, a casing about the gearing defining a reservoir for lubricant about the gears where they are meshed, a pump driven by the driving gear, and connections to the pump for supplying lubricant from the reservoir to said bearings.

5. In an extruding apparatus, a screw

- 5 journaled in a housing, a hopper over the screw adjacent the inner side of the housing, driving means in the housing for actuating the screw, said housing providing a reservoir for containing a lubricant, means for supplying lubricant from the reservoir to the screw bearings, and a separator acting on the screw between the hopper and the inner bearing for the screw to keep the lubricant in and the dirt out, said separator comprising a wedge-shaped element yieldingly urged against the screw. 70
- 10 6. In an extruding apparatus, a sleeve, a driven quill journaled therein, an extruding passage, and a screw therein, said screw being connected at one end in the quill to be driven thereby, said connection being loose to permit slight movement of the screw out of exact alignment with the quill whereby considerable strain is relieved from the quill bearings. 75
- 15 20 7. In an extruding machine, a screw, a driven quill holder keyed loosely thereto, a sleeve member in which the screw and the quill are journaled, said member supporting therein bearings for the quill at each end thereof and also an intermediate thrust bearing between shoulders on the sleeve and quill, a worm gear journaled about said member and having driving connection with the quill at the end thereof, a driving worm meshed with the worm gear at the bottom thereof. 80
- 25 30 8. In an extruding machine, a housing and a sleeve having aligned axial bores, a quill, means radially journalling said quill at both ends thereof in said sleeve member, intermediate thrust bearing means between shoulders on the sleeve and quill, a screw loosely keyed in said quill and carried in said housing, a worm gear journaled on said sleeve, a flange ring securing said quill to said worm gear, and a worm for driving said worm gear. 85
- 35 40 9. In an extruding machine, a housing and a sleeve having aligned axial bores, a quill, means radially journalling said quill at both ends thereof in said sleeve member, intermediate thrust bearing means between shoulders on the sleeve and quill, a screw loosely keyed in said quill and carried in said housing, a worm gear journaled on said sleeve, a flange ring securing said quill to said worm gear, a worm for driving said worm gear, means for lubricating said bearings, and a separator ring between said screw and said quill to keep the lubricant in the bearings and the dirt out. 90
- 45 50 55 10. In an extruding machine, a housing and a sleeve having aligned axial bores, a quill, means radially journalling said quill at both ends thereof in said sleeve member, intermediate thrust bearing means between shoulders on the sleeve and quill, a screw loosely keyed in said quill and carried in said housing, a worm gear journaled on said sleeve, a flange ring securing said quill to 100
- 60 65 105 110 115 120 125 130
- said worm gear, a worm for driving the worm gear, means for lubricating said bearings, and a separator ring between said screw and said quill to keep the lubricant in the bearings and the dirt out, said separator ring including a wedge-shaped element yieldingly urged against the quill. 70
11. In an extruding machine, a housing, a screw, means including a quill connected to the screw for journaling the screw in the housing, a hopper on said housing, means for lubricating said journaling means, and a separator ring between said hopper and said journaling means to keep the lubricant in said journaling means and the dirt out, said separator ring including a wedge-shaped element yieldingly urged against the quill. 80
